(57) **CLAIM**

The ornamental design for a food mixing agitator, as shown and described.

DESCRIPTION

FIG. 1 is a front, top, right side perspective view of a food mixing agitator showing our new design;

FIG. 2 is a rear, bottom, left side perspective view thereof;

FIG. 3 is a top plan view thereof;

FIG. 4 is a front elevational view thereof, the rear elevational view being identical to FIG. 4;

FIG. 5 is a bottom plan view thereof; and,

FIG. 6 is a right side elevational view thereof, the left side elevational view being identical to FIG. 6.
